(57) **CLAIM**

The ornamental design of the watering apparatus, as shown and described.

DESCRIPTION

FIG. 1 is a perspective view of the watering apparatus showing my new design;

FIG. 2 is a perspective view of the watering apparatus detached;

FIG. 3 is a perspective view of a second embodiment of the watering apparatus shown in FIG. 1;

FIG. 4 is an enlarged perspective view of the watering apparatus of FIG. 3;

FIG. 5 is a top plan view of FIG. 4;

FIG. 6 is a sectional view taken along line 6—6 of FIG. 5; FIG. 7 is a side elevational view of the right side of FIG. 4; FIG. 8 is a side elevational view of the left side of FIG. 4; FIG. 9 is a front elevational view of FIG. 4;

FIG. 10 is a rear elevational view of FIG. 4;

FIG. 11 is a bottom plan view of FIG. 4;

FIG. 12 is an axonometric of FIG. 4;

FIG. 13 is a perspective view of a third embodiment of the watering apparatus of FIG. 1;

FIG. 14 is a perspective view of the watering apparatus detached;

FIG. 15 is a perspective view of a fourth embodiment of the watering apparatus;

FIG. 16 is an enlarged perspective view of the water apparatus of FIG. 15;

FIG. 17 is a top plan view of FIG. 16;

FIG. 18 is a sectional view taken along line 18—18 of FIG. 17;

FIG. 19 is a side elevational view of the left side of FIG. 16;

FIG. 20 is a side elevational view of the left side of FIG. 16;

FIG. 21 is a front elevational view of FIG. 16;

FIG. 22 is a rear elevational view of FIG. 16;

FIG. 23 is a bottom plan view of FIG. 16; and,

FIG. 24 is an axonometric view of FIG. 16.

The watering apparatus is shown detached in FIGS. 2 and 14 for clarity of illustration.

The broken line showing of trees and water drop is for illustrative purposes only and forms no part of the claimed design.
